UNITED STATES PATENT OFFICE

JOHN MAUM, OF ANSONIA, CONNECTICUT.

DEVICE FOR STRAIGHTENING EXTRUDED SHAPES.

Application filed June 8, 1925. Serial No. 35,836.

This invention relates to a straightening device for irregular extruded shapes, and has for an object to provide a device which may be operated by power for straightening these irregular shapes and thus do away with the hand straightening operation now generally employed for this type of articles.

It is also an object of the invention to provide a power straightening means which may be adjusted to take different sizes of dies required for straightening different shapes, and thus to reduce the amount of metal required for the dies.

With the foregoing and other objects in view, I have devised the construction illustrated in the accompanying drawings forming a part of this specification, similar reference characters being employed throughout the various figures to indicate corresponding elements. In these drawings,

Fig. 1 is a front elevation of the straightening device, certain parts thereof being broken away to more clearly show the construction, and the base being shown in section, the plane of the figure being substantially on line 1—1 of Fig. 3.

Fig. 2 is a top plan view of my improved straightening device.

Fig. 3 is a side elevation of the device with portions broken away to more clearly show the construction.

Fig. 4 is a transverse section substantially on line 4—4 of Fig. 3, and

Fig. 5 is a transverse section substantially on line 5—5 of Fig. 3.

In forming extruded shapes and moldings the hot metal is forced through a die, the shape of the die, of course, being made to correspond with the cross section of the bar or molding, and as these extruded bars cool the metal shrinks and warps, causing it to get out of the proper shape. At the present time these bars are straightened by hand, which is an expensive operation. To reduce the expense of straightening these bars and also to increase production I have devised a power straightener through which these irregular shapes may be run with a continuous operation, and will be straightened as they are pressed through the device.

One embodiment of the invention is illustrated in the accompanying drawings and comprises a bed or base 10 having mounted thereon adjustable blocks 11 for holding the straightening dies 12 and 13. These dies are located one above the other as shown in

Fig. 1, and are shaped on their opposed surfaces to substantially correspond with the shape of the upper and lower surfaces of the bar or member 14 to be straightened. 60

In the drawing I have shown the bar as a plain angle bar, but it is to be understood that this bar is shown merely for the purpose of illustration, and practically any of the extruded shapes may be straightened 65

in the same manner. As a convenient mounting for the dies and the blocks 11 the base is provided with a transverse guideway 15 in which the blocks 11 are mounted, and the lower die 12 may also be set in this 70

guideway between the blocks. The opposed faces of the blocks 11 are provided with vertical guideways, in the present instance grooves 16, for the ends of the dies. The blocks 11 may be adjusted toward and from 75

the dies by suitable means such as adjusting screws 17 threaded into the blocks and mounted in suitable bearing blocks 18 mounted on the base, as shown. It will be apparent that by rotating these screws the 80

blocks 11 may be adjusted inwardly and outwardly toward and from each other and the dies 12 and 13. It will thus be apparent that dies having different lengths may be mounted between the blocks, and therefore, 85

for small dies or dies for small shapes a great deal less metal may be used than would be the case if the blocks 11 were stationary and placed in a position to accommodate the largest dies. Thus with my 90

construction no more metal is used in the die than that required for the die proper and, of course, the guiding ends thereof.

When the device is in operation the lower die 12 is stationary while the upper die 13 is movable up and down. Means are provided for lifting this die off from the bar 14, such as the springs 19, which are connected to the upper die and also suitable supports 20 at the top of the blocks 11. 95 These supports and the blocks 11 extend through suitable housings 21 mounted on the base, and set screws 22 carried by these housings are employed to clamp these supports 20 in proper adjusted positions. It is 100

to be noted that the springs are sufficiently strong to lift the upper die 13 away from the bar to be straightened and the upward movement of the die is limited by adjustable stop screws 23. Mounted above the upper die is a power means for continuously imparting blows to or hammering the 110

upper side of this die to force it against the bar 14 to be straightened and to press this bar between the surfaces of the two dies to thus straighten the bar which is being passed between the two dies. This power means in the device shown comprises a steam hammer 24, shown merely in outline, the plunger of the hammer being shown at 25. During the straightening operation the bar 14 is passed continuously between the dies, either by hand or some power feeding means, and the hammer operates continuously to force the upper die against the bar to thus straighten it and give it the proper shape. If it is found not to be feasible to pass the bar through the die by hand some suitable power means may be provided such as a chain operated by a suitable power means.

20 For best results the bar 14 should be guided both before entering the dies and after it leaves them. For this purpose I have provided both on the front and rear sides of the dies two pairs of upper and lower guiding rolls 26 and 27 for the upper and lower sides of the bar, and these rolls are mounted in bearings 28 which are vertically adjustable in frames 29. A convenient means of adjusting these rolls are screws 30 and 31 having threaded engagement with the bearings and operated by a rod 32 with which they are connected by the beveled gears 33. By rotating the rod through a crank or other suitable means the rolls may be adjusted up and down to the proper location. Between the two sets of rolls is a pair of lateral guides 34. These guides are mounted in guides 35 on the base 10 and may be adjusted toward and from the lateral sides of the bar by means of the screws 36 carried by suitable supports 37 secured to the base. It will thus be apparent that the bar while passing through the dies will be rigidly held and guided in proper relation to the dies by means of the guide rollers 26 and 27 and the guides 34, and that these rollers and guides may be easily and quickly adjusted for bars of different sizes and shapes.

50 It will be apparent from the foregoing description that I have devised a simple and effective power operated means for straightening these extruded shapes and moldings by a continuous operation, and that, therefore, the greater portion of the hand operations for straightening these bars now generally required will be eliminated. This will, therefore, not only reduce the cost of production but will also increase the amount of production.

Having thus set forth the nature of my invention, what I claim is:

1. In a device for straightening bars of metal, a pair of dies having opposed faces shaped to substantially correspond with the

transverse contours of the opposite sides of the bar to be straightened, said dies being so arranged that the bar may be passed transversely between them from one side of the dies to the other side during the straightening operation, one of said dies being movable toward and from the other die and said dies being in alignment in the direction of movement of the movable die, and means for hammering the movable die to force it toward the other die and against the bar to be straightened while extending between the dies.

2. In a device for straightening bars of metal, a pair of dies having opposed faces shaped to substantially correspond with the transverse contours of the opposite sides of the bar to be straightened, said dies being so arranged that the bar may be passed transversely between them from one side of the dies to the other side during the straightening operation, one of said dies being movable and said dies being in alignment in the direction of movement of the movable die, yielding means tending to move the movable die away from the other die, and means for hammering the movable die to force it against the bar to be straightened while extending between the dies.

3. In a device for straightening bars of metal, a pair of upper and lower dies having their opposed faces shaped to substantially correspond with the transverse contours of the opposite sides of the bar to be straightened, said dies being so arranged that the bar may be passed transversely between them from one side of the dies to the other side during the straightening operation, the upper die being movable vertically, movable guide blocks for the dies at the opposite ends thereof, means for shifting said guide blocks to receive dies of different lengths, and a power means for hammering the upper die to force it against the bar to be straightened while extending between the dies.

4. In a device for straightening bars of metal, a pair of upper and lower dies having their opposed faces shaped to substantially correspond with the transverse contours of the opposite sides of the bar to be straightened, said dies being so arranged that the bar may be passed transversely between them from one side of the dies to the other side during the straightening operation, the upper die being movable vertically, movable guide blocks at the outer ends of the dies, said blocks having upright guide ways for the ends of the dies, means for adjusting the blocks toward and from the dies, and a power means for hammering the upper side of the upper die.

5. In a device for straightening bars of metal, a pair of upper and lower dies arranged in superposed relation and having

- their opposed faces shaped to substantially correspond with the transverse contours of the opposite sides of the bar to be straightened, said dies being so arranged 5 that the bar may be passed transversely between them from one side of the dies to the other side during the straightening operation, the upper die being movable vertically and said dies being in vertical alignment, 10 springs connected to the upper die to hold it spaced above the lower die, and power means for hammering the upper side of the upper die.
6. In a device for straightening bars of metal, a pair of upper and lower dies having their opposed faces shaped to substantially correspond with the transverse contours of the opposite sides of the bar to be straightened, said dies being so arranged 15 20 25 30 35 40 that the bar may be passed transversely between them from one side of the dies to the other side during the straightening operation, the upper die being movable vertically, springs connected to the upper die to hold it spaced above the lower die, movable guide blocks at the opposite ends of the dies, means for adjusting the blocks toward and from the dies, said blocks being provided with vertical guide ways for the upper die, and power means for hammering the top of the upper die.
7. In a device for straightening bars of metal, a base having a transverse guide way, a pair of blocks mounted to slide in said 45 50 55 60 65 70 75 80 85 guide way, a pair of upper and lower dies having their opposed faces shaped to substantially correspond with the transverse contours of the opposite sides of the bar to be straightened, said dies being so arranged that the bar may be passed transversely between them from one side of the dies to the other side during the straightening opera-
- tion, said blocks being provided with upright guide ways on their inner walls for the ends of the dies, means for adjusting the blocks toward and from the dies, yielding means tending to lift the upper die, and power means for hammering the top of the upper die.
8. In a straightening device of the character described, a base, a pair of blocks adjustably mounted on said base, means for adjusting the blocks toward and from each other, upper and lower dies between said blocks, said blocks being provided with upright guideways for the ends of the dies, springs tending to lift the upper die, adjustable stop means for limiting the upward movement of said die, and means for hammering the top of the upper die.
9. In a straightening device of the character described, a pair of vertically spaced dies located in superposed relation, the upper die being movable vertically and said dies being in vertical alignment, springs tending to lift the upper die, power means for hammering the top of the upper die, and adjustable guides for the member to be straightened located to the front and rear of said dies.
10. In a straightening device of the character described, a pair of vertically spaced dies, the upper die being movable vertically, springs tending to lift the upper die, power means for hammering the top of the upper die, guide rollers for the top and bottom of the member to be straightened, means for adjusting the rollers toward and from each other, guides for the lateral sides of the member to be straightened, and means for adjusting these latter guides toward and from each other.

In testimony whereof I affix my signature.
JOHN MAUM.
